IGNITION CONTROLLING DEVICE FOR INTERNAL COMBUSTION ENGINES

Manuel H. Elkin, Elmira Heights, N. Y., assignor
to Bendix Aviation Corporation, South Bend,
Ind., a corporation of Delaware

Application August 22, 1940, Serial No. 353,663

9 Claims. (Cl. 74—472)

The present invention relates to an ignition controlling device for internal combustion engines and more particularly to a device for momentarily grounding the ignition circuit of an internal combustion engine while a variable speed transmission operated thereby is being automatically shifted.

In devices of this character it is desirable to have some means for rehabilitating the ignition system of the engine after a predetermined time delay in case the automatic transmission fails for any reason to complete its shifting operation.

It is an object of the present invention to provide an ignition controlling device incorporating novel means for restoring the operative condition of the engine after a predetermined time interval.

It is another object to provide such a device which is reliable and uniform in operation while being simple and economical in construction.

Further objects and advantages will be apparent from the following description taken in connection with the accompanying drawings in which:

Fig. 1 is a semi-diagrammatic representation of an internal combustion engine and transmission with a preferred embodiment of the invention applied thereto for controlling the ignition system of the engine;

Fig. 2 is a top view partly in section of a preferred form of thermostatic controlling device;

Fig. 3 is a side elevation of the same partly in vertical section;

Fig. 4 is an end view of the thermostatic control device from the left on line 4—4 in Fig. 3, the casing being sectioned; and

Fig. 5 is an end view from the right in Fig. 3.

In Fig. 1 of the drawings there is illustrated in dotted lines the outline of an internal combustion engine 1 with clutch housing 2 and variable speed transmission 3 operated thereby, all being understood to be of conventional construction. An automatic controlling device 4 for the transmission 3 is mounted thereon in any suitable manner and comprises a shift rail 5 adapted to engage a shift arm 6 of the transmission to effect the changes in speed ratio. The variable speed transmission and its control form no part of the present invention and further description thereof is accordingly deemed unnecessary.

The engine 1 is provided with an ignition system of conventional type comprising a battery 7 grounded at 8 and connected through an ignition switch 9 to the primary of an induction

coil 11, the secondary of which is connected to the spark plugs of the engine in the usual manner. The ignition circuit from the primary of the induction coil 11 is completed through a lead 12 to a timer 13 grounded at 14.

According to the present invention, means are provided for grounding the lead 12 of the ignition circuit during the shifting operation of the transmission in order to facilitate the operation by momentarily relieving the transmission of the driving force of the engine. As here illustrated, a grounding circuit is provided comprising a lead 15 connected to ignition lead 12, a fixed contact 16, a contact 17 mounted on a spring arm 18 so as to normally engage the contact 16, a lead 19 and a grounding switch indicated generally by numeral 21. Switch 21 comprises a fixed contact 22, a ground contact 23 and a bridging contact 24. Contact 24 is normally disengaged from the fixed contacts and is mounted on a slidable plunger 25, the lower end of which normally rests in a notch 26 in the shift rail 5. The parts are so proportioned that initial sliding movement of the shift rail 5 to perform its shifting function, raises the plunger 25 and bridging contact 24 to close the switch 21 and hold it closed until the movement of the shift rail is completed. At that time, a second notch 27 in the shift rail comes into registry with the lower end of the plunger 25, thereby permitting the switch 21 to open.

Means are provided for opening the normally closed contacts 16, 17 after a short predetermined time interval so as to break the ignition grounding circuit and rehabilitate the engine ignition circuit irrespective of the completion of the shifting movement of the transmission. As here shown, this is accomplished by means of a spring arm 28 adapted to engage a block of insulation 29 on the contact arm 18 and flex the arm 18 to move contact 17 out of engagement with contact 16. This action of the arm 28 is, however, normally restrained by a wire 31 attached at 32 to the free end of arm 28 and securely anchored at 33 at a point above and adjacent to the anchorage of the arm 28. Wire 31 is made of suitable thermally expansive material such as tungsten, and means are provided for heating the wire to cause it to expand and permit the spring arm 28 to open contacts 16, 17. As here shown, this means is in the form of a heating circuit comprising a lead 34 connected to the ignition switch 9, and to the wire 31 through a resistor 35. Resistor 35 is of such

value as to secure the desired rate of heating of wire 31 in order to control the time interval for the opening of the contacts 16, 17. The heating circuit for wire 31 is completed through the spring arm 28 and a lead 36 to a fixed contact 37 in grounding switch 21, whereby closure of the switch 21 causes the bridging contact 24 thereof to connect the contact 37 to the ground contact 23.

The thermostatic controlling device including the contacts 16, 17, is preferably formed as illustrated in Figs. 2 to 5 inclusive. As there illustrated, a mounting plate 38 of insulating material serves to support a bracket 39, the inner end of which carries the fixed contact 16 and the outer end of which supports the spring arm 18 carrying movable contact 17. Bracket 39 also supports the spring arm 28 for opening the contacts and has a laterally extending arm 41 having a flared opening 42 adapted to receive the anchorage 33 of the wire 31. The anchorage 33 preferably takes the form of a bead of fuseable insulating material such as borax glass which is fused on the wire within the opening 42 while the wire is maintained under tension. A terminal 43 is provided for attachment of lead 34, a terminal 44 for attachment of lead 19, a terminal 45 for attachment of lead 15, and a terminal 46 for attachment of lead 36. The entire unit is preferably encased in a metal cup 47 fixed to the plate 38 in any suitable way as by means of a clamping ring 48.

In operation, closure of the ignition switch 9 renders the ignition circuit of the engine operative in the usual manner, the grounding circuit for the ignition being open at switch 21, and the heating circuit for the wire 31 being also open at said switch. Upon initiation of the shifting movement of rail 5, switch 21 is closed, thereby grounding the ignition circuit of the engine through lead 15, contacts 16, 17, lead 19, switch contacts 22, 24 and 23 to the ground. At the same time, the heating circuit for the wire 31 is completed through lead 34, resistor 35, lead 36, switch contacts 37 and 24 to the ground contact 23 so that the wire 31 begins to heat up. If the shifting operation takes place in the normal manner, it is completed in a few tenths of a second, and the plunger 25 of switch 21 falls into the notch 27 of the shift rail 5, thus opening switch 21. If, for any reason, the shifting operation is not completed, however, and the rail 5 stops at an intermediate point, the wire 31 becomes heated sufficiently to expand and permit the spring arm 28 to push contact 17 out of engagement with contact 16, thus opening the grounding circuit for the engine ignition and restoring the operation of the engine. The heating circuit for wire 31 remains closed as long as switch 21 is held closed, so that there is no possibility of undesired grounding of the engine ignition.

It will be readily appreciated that since the mass of the wire 31 is very small, the heating up and cooling off of the wire may take place quite rapidly, so that any suitable short time interval for the opening of contacts 16, 17 may readily be secured, and this time interval will be substantially constant even though the device is repeatedly operated.

Although but one form of the invention has been shown and described in detail, it will be understood that other forms are possible and various changes may be made in the design and arrangement of the parts without departing

from the spirit of the invention as defined in the claims appended hereto.

What is claimed is:

5 1. In combination with an ignition system of an internal combustion engine, a normally open grounding circuit therefor including a pair of normally closed contacts, spring means for opening the contacts, a tension wire of thermally expansive material restraining the spring means from opening the contacts, means for closing the grounding circuit, and means for heating the wire to cause it to release the spring means.

10 2. In combination with an ignition system of an internal combustion engine, a normally open grounding circuit therefor including a pair of normally closed contacts, spring means for opening the contacts, a tension wire of thermally expansive material restraining the spring means from opening the contacts, means for closing the grounding circuit, and means rendered operative by completion of the grounding circuit for heating the wire to cause it to release the spring means after a predetermined time interval.

15 3. In combination, an internal combustion engine having an electrical ignition system, a variable speed transmission driven thereby, a grounding circuit for the ignition system including a pair of normally closed contacts and a normally open switch, means for closing the switch during shifting of the variable speed transmission, spring means for opening the contacts, restraining means for the spring means including a tension wire of thermally expansive material, and means for heating the wire to cause it to release the spring means.

20 4. In combination, an internal combustion engine having an electrical ignition system, a variable speed transmission driven thereby, a grounding circuit for the ignition system including a pair of normally closed contacts and a normally open switch, means for closing the switch during shifting of the variable speed transmission, spring means for opening the contacts, restraining means for the spring means including a tension wire of thermally expansive material, and means rendered operative by closure of said switch for heating the wire to cause it to release the spring means after a predetermined time interval.

25 5. In combination with an internal combustion engine and an automatic variable speed transmission operated thereby, an ignition system for the engine, a grounding circuit for the ignition system including a normally open switch and a set of normally closed contacts, means responsive to the initiation of the shifting movement of the transmission for closing said switch to complete the grounding circuit, spring means for opening the contacts, a thermally expansive wire restraining said opening means, and means responsive to shifting of the transmission for heating the wire to cause it to release the opening means.

30 6. In combination with an internal combustion engine and an automatic variable speed transmission operated thereby, an ignition system for the engine, a grounding circuit for the ignition system including a normally open switch and a set of normally closed contacts, means responsive to the initiation of the shifting movement of the transmission for closing said switch to complete the grounding circuit, spring means for opening the contacts, a thermally expansive wire restraining said opening means, and a heating

circuit for said wire including said normally open switch.

7. In an ignition controlling device for internal combustion engines, means for rendering the ignition system of the internal combustion engine inoperative, means for restoring the operability of the ignition system after a predetermined time including an elastic member and a thermally expansive wire normally restraining the elastic member, and means for heating the wire responsive to actuation of the first-named means.

8. In combination with an internal combustion engine and a variable speed transmission operated thereby, means for rendering the ignition system inoperative during shifting of the transmission, means for restoring the operability of the ignition system after a predetermined

time irrespective of the position of the transmission including an elastic member and a thermally expansive wire normally restraining the elastic member, and means for heating the wire when the transmission is intermediate any of its operative positions.

9. In an ignition controlling device for internal combustion engines, means for rendering the ignition momentarily inoperative including a switch, and means for restoring the operability of the ignition system after a predetermined time interval including an elastic member and a thermally expansive wire normally restraining the elastic member, and means for heating said wire rendered operative by actuation of said switch.
